United States Patent

Des. 236,860
Patented Sept. 23, 1975

236,860

DISPLAY UNIT

Martin M. Berger, Elkins Park, Pa., assignor to
Leg Lure, Inc., Fort Washington, Pa.

Filed Dec. 7, 1973, Ser. No. 422,634

Term of patent 14 years

Int. Cl. D20—02

U.S. Cl. D6—25

FIG. 1

FIG. 3

FIG. 2

FIG. 4

FIG. 5

FIG. 1 is a perspective view of a display unit in accordance with the present invention;

FIG. 2 is a left side elevation view thereof;

FIG. 3 is a top plan view thereof;

FIG. 4 is a bottom view thereof;

FIG. 5 is a side elevation view of an alternative embodiment of the invention wherein the display unit is free standing rather than counter supported. The top plan and bottom view of this embodiment are identical to FIGS. 3 and 4 respectively. The undisclosed side elevation and front and back views of this embodiment are identical to the side elevation view in FIG. 5.

The undisclosed right side elevation and the front and back views are identical to the left side elevation view of FIG. 2.

I claim:

The ornamental design for a display unit, substantially as shown and described.
